UNITED STATES PATENT OFFICE.

HARRY E. BLANCHARD, OF LOWELL, MASSACHUSETTS, ASSIGNOR TO SACO-Lowell
SHOPS, OF BOSTON, MASSACHUSETTS, A CORPORATION OF MASSACHUSETTS.

ROLL-SUPPORT FOR SPINNING, TWISTING, OR LIKE MACHINES.

1,094,697.

Specification of Letters Patent. Patented Apr. 28, 1914.

Application filed January 30, 1913. Serial No. 745,085.

To all whom it may concern:

Be it known that I, HARRY E. BLANCHARD, of Lowell, in the county of Middlesex and State of Massachusetts, a citizen of the 5 United States, have invented a new and useful Improvement in Roll-Supports for Spinning, Twisting, or like Machines, of which the following is a full, clear, and exact description, reference being had to the 10 accompanying drawings, forming a part of this specification, in explaining its nature.

The present invention relates to improvements in devices for supporting the top carrier rolls used in spinning, twisting, or like 15 machines.

Among the objects of the present invention is to provide a roll support that will be very strong and durable and will thereby overcome some of the objectionable weaknesses in devices hitherto employed for the 20 same purpose; to provide a roll support that will efficiently hold the rolls in their proper places and accurately position the same, and to provide, also, a support having easy and 25 accurate adjustments, thereby providing for a satisfactory adjustable retention of the rolls.

It is a further object of my invention to provide a construction made up of a variety 30 of assembled parts and especially parts made of rolled steel of standard stock and which require no special preformation, and possessing the further advantage that any of the parts, especially those subject to wear, 35 may be hardened, or any of the parts may be replaced without difficulty.

My invention can best be seen and understood by reference to the drawings, in which—

40 Figure 1 represents in side elevation a roll stand provided with a top roll support embodying my invention. Fig. 2 is a plan of the roll support and top rolls supported thereby, with portions thereof broken away.

45 Fig. 3 is a section on the line 3—3 of Fig. 2. Fig. 4 is a section on the line 4—4 of Fig. 3. Fig. 5 is a rear elevation of a portion of the device to which special reference will hereinafter be made, and Fig. 6 is a section 50 on the line 6—6 of Fig. 2.

In the drawings, 1 represents the roll support upon which are mounted the bottom rolls and of which 2 represents the front roll, 3 the middle and 4 the back roll. As is

customary the middle and back rolls are 55 supported in and between the adjustable parts 5 of the stand to permit adjustment or variation in the distance between the front and middle rolls. Upon the adjustable parts 5 of the stand is mounted the roll support comprising my invention and which operates to position the top rolls 6, 7 and 8, respectively. The roll support is constructed as follows, in which connection it will be understood that the support is capable of 60 holding and positioning a plurality of series of top rolls, only one series, however, being shown for purposes of illustration.

9 represents a carrier bar which preferably consists of a rolled channel bar of inverted U shape. This bar is interposed between the adjustable portions 5 of the stand and pivotally secured thereto in a manner to be later explained. Secured to this bar and projecting laterally therefrom are 70 fingers 10. These fingers are preferably rolled bars rectangular in cross section and provided with downturned end portions which enter holes 11 formed in the head of the carrier bar and engage the inner surfaces of the sides of this bar to which the fingers are secured by welding or in any other suitable manner.

75 Each finger has adjustably mounted thereon an extension 12. These extensions are 80 preferably rolled bars of uniform cross section and are mounted upon the respective fingers to longitudinally extend the same. The fingers 10 and extensions 12 thereof operate to retain and position the top rolls for 85 which purpose the bars are separated from one another a sufficient distance so that the top rolls may be interposed to turn between adjacent fingers and their extensions.

90 Secured to each of the fingers 10 are 95 flanged metal pieces or strips which extend along and above the respective fingers and perform the double function of guiding the extensions 12 and forming bearings for the middle and back top rolls 7 and 8, respectively. Of these pieces or strips the one 13 is provided with a flange 16, the one 14 with flanges 17 and 18 and the one 15 with a flange 19. The flanges 16 and 17 provide 100 open bearings for the back roll 8; the flanges 18 and 19 open bearings for the middle roll 7.

105 Secured to each of the extensions 12 are

flange-forming pieces 20 and 21, respectively forming open bearings for the front top roll.

All of the flanged strips or pieces secured to the fingers and their extensions are preferably made of sheet metal and secured to the fingers and extensions by welding. They may, however, be secured thereto in any other suitable manner.

10 Each of the extensions is adjustably secured to the finger of which it is an extension by means of an inverted U-shaped clamp member 22. This member straddles the extension and is fixed to the finger 10 outside the strips 14 affixed thereto by welding or otherwise. Passing through the head of the clamp is a screw 23 which bears against the top side of the extension and, upon tightening the same is adapted to hold 15 the extension in any adjusted position.

It will be understood of course that the end fingers of the carrier bar have top rolls only upon one side and for the purpose of retaining the extension of these end fingers 25 each is provided on the outside with a single strip or piece 24 which extends above the finger and assists in forming a guide for the extension. These strips 24 are preferably made of sheet metal and secured to the fingers 30 in the same manner as the other strips or pieces.

The carrier bar is pivoted to the parts 5 of the roll stand by means of studs 25 secured one in each end of the carrier bar; one 35 only of these studs being shown for purposes of illustration. Each of the studs comprises a rectangular part 26 and a circular part 27. The rectangular part of the stud enters the end of the carrier bar and becomes 40 secured thereto by having the two opposite sides thereof engage the inner side walls of the bar, and a third side engage the lower turned end of one of the fingers 10, and to which parts the stud may be secured by 45 welding or otherwise. The circular part of the stud is adapted to enter an open slot 28 in the portion 5 of the stand. (See Fig. 1.)

Practically all of the parts entering into the construction of the support are of standard commercial shapes. Thus the carrier 50 bar 9, fingers 10 and extensions 12 are commercial rolled bars or rods of uniform cross section throughout, while the various strips or pieces secured to the fingers and their 55 extensions are of ordinary sheet metal. Any of the parts may be hardened to resist wear, and especially those sheet metal parts which provide bearings for the top rolls.

Having thus fully described my invention, 60 I claim and desire to secure by Letters Patent of the United States:—

1. A support for top rolls of the character specified comprising a carrier bar, fingers secured thereto and projecting therefrom, 65 top rolls interposed between said fingers, and

formed flanged pieces fixed to and spaced along that side of each finger facing said top rolls, said pieces providing bearings for said rolls.

2. A support for top rolls of the character 70 specified, comprising a carrier bar, fingers secured thereto and projecting therefrom, said fingers being spaced from one another along said bar whereby a series of top rolls may be interposed between adjacent fingers, 75 and flanged pieces secured to said fingers, said pieces being spaced from one another along said fingers, each piece providing one side of an open bearing for a top roll.

3. A support for top rolls of the character 80 specified, the same having a carrier bar, fingers secured thereto and projecting therefrom, said fingers being spaced from one another along said bar whereby said top rolls may be interposed to turn between adjacent 85 ones of said fingers, an extension adjustably secured to each one of said fingers, flanged pieces carried by said fingers and providing both a guide for said extensions and bearings for a portion of said rolls, and flanged 90 pieces carried by each of said extensions and providing bearings for others of said rolls.

4. A support for top rolls of the character 95 specified, the same having a carrier bar, fingers secured thereto and projecting therefrom, said fingers being spaced from one another along said bar whereby the top rolls may be interposed between adjacent ones of 100 said fingers, flanged strips secured to said fingers, the bodies of which strips are adapted to form a guideway over said fingers and the flanged parts of said strips to form bearings for supporting a portion of said rolls, extensions to said fingers contained in part 105 in said guideways and adjustable longitudinally therein, means for adjustably securing said extensions to said fingers, and flanged pieces carried by said extensions and providing 110 bearings for others of said rolls.

5. A support for top rolls of the character specified, the same having a carrier bar of uniform cross section, fingers of uniform cross section secured thereto and projecting therefrom, extensions to said fingers of uniform cross section adjustably mounted thereon, flanged sheet metal strips secured to said fingers and forming in part guideways for said extensions and in other part bearings for a portion of said rolls, flanged sheet 115 metal pieces secured to said extensions and forming bearings for others of said rolls, and means for adjustably securing said extensions to said fingers.

6. A support for top rolls having a channel bar of uniform cross section with holes therein, spaced fingers secured to said bar to project therefrom, said fingers being formed to extend through the holes in said bar and engage the interior thereof, and 120 125

means carried by said fingers for holding and positioning said top rolls.

7. A support for top rolls of the character specified, the same having an inverted U-shaped carrier bar with holes therein, fingers secured to said bar to project therefrom, said fingers entering the holes in said bar to engage the interior walls thereof, extensions adjustably mounted upon said fingers, flanged sheet metal strips secured to said fingers and forming in part guideways for said extensions and bearings for a portion of said top rolls, flanged sheet metal pieces secured

to said extensions and forming bearings for other of said top rolls, means for adjustably 15 securing said extensions to said fingers, and a pivoted stud at each end of said carrier bar having a rectangular part engaging the sides of said bar, and a circular part projecting beyond the end of said bar and forming trunnions on which said bar may turn. 20
